CLAIM

The ornamental design for a hand-held vacuum cleaner as shown and described.

DESCRIPTION

FIG. 1 is a front elevational view of a hand-held vacuum cleaner showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a bottom, rear and left side perspective view thereof; and,

FIG. 9 is an enlarged view of portion 9 in FIG. 7.

The even-dash broken lines in the drawings illustrate portions of the hand-held vacuum cleaner which form no part of the claimed design. The dash-dot-dot broken lines illustrate the boundary of the enlarged views and form no part of the claimed design.
